UNITED STATES PATENT OFFICE.

JOHN SYRCHER, OF BUFFALO, NEW YORK.

DESIGN FOR A BILLIARD-TABLE.

Specification forming part of Design No. 6,278, dated November 26, 1872.

To all whom it may concern:

Be it known that I, JOHN SYRCHER, of Buffalo, in the county of Erie and State of New York, have invented a Design for Billiard-Tables, of which the following is a specification:

The nature of my design is fully represented in the accompanying photographic illustration, to which reference is made.

The panels of the frame are bounded oval curves, and above the legs are ovals, within which are carved figures. The sides of the frame incline upward and outward, and the

corners thereof are of the form shown in the photograph.

Having described my invention or new design, I claim—

A design for billiard-tables, substantially in the manner above described and shown.

In witness whereof I have hereunto subscribed my name this 16th day of May, 1872.

JOHN SYRCHER.
